TOILET SEAT

Filed Feb. 25, 1932

UNITED STATES PATENT OFFICE

EMIL KLUMPP, OF DETROIT, MICHIGAN

TOILET SEAT

Application filed February 25, 1932. Serial No. 595,099.

This invention relates to improvements in closet seats. It is an object of the invention to provide a closet seat which is composed of a plurality of pieces of material, preferably wood, which are held together in a novel manner so that once they have been assembled they cannot again be taken apart.

Other objects of the invention are to provide a closet seat consisting of a plurality of parts wherein metallic engaging members are secured in recesses formed in the contiguous faces of the separate parts so as to provide a strong form of joint; wherein the pivotal arms which support the seat are held in position against the underside of the seat by screws which are in threaded engagement with said members; and wherein the conventional seat stops are also mounted in plates secured to the said engaging members; and wherein the metallic engaging members are secured in position by fastening means which extend some distance into the seat parts and substantially at right angles to the joints thereby holding the said members firmly to their respective parts.

Yet another object of the invention is to provide a closet seat wherein, as the respective parts are moved into place, they are automatically engaged by springs which prevent any further independent movement of any of the parts relative to one another.

A further object of the invention is to provide a relatively simple form of seat wherein the adjacent margins of the seat parts are so reinforced that opening of the joints is not liable to occur.

With these and other objects and advantages in view which will become apparent as the specification proceeds, the invention is hereinafter more fully described with the aid of the accompanying drawing, in which:

Figure 1 illustrates a plan view of the seat.

Figures 2, 3 and 4 show enlarged views, namely front elevation, side elevation and plan respectively, of one of the joint portions.

Figures 5, 6 and 7 show enlarged views, namely front elevation, side elevation and plan respectively, of the other seat part.

Figure 8 is an enlarged section on the line 50 8—8 of Figure 1.

Figure 9 is an enlarged view showing a slightly varied arrangement of the flat connecting spring, and

Figure 10 is a modified arrangement, shown in an enlarged sectional view, of the spring holding arrangement wherein a spiral spring is employed.

Referring to the drawing, 1 designates a closet seat consisting of a plurality of flat pieces of material, usually wood, which are indicated by the ordinals 2, 3, 4 and 5. As the joints between each pair of contiguous faces of these pieces is the same I will first describe the joint between the pieces 2 and 3.

In the faces of the pieces 2 and 3 which lie contiguous to one another slots 6 and 7 are formed to receive cooperating members 8 and 9 respectively which are preferably made of metal. The outer faces of these members are provided with cooperating dovetails 10 and 11 formed thereon, which are longitudinally tapered, and, in order to bring these dovetail portions into engagement the contacting faces of the pieces 2 and 3 are so formed at 10a and 11a respectively as to constitute continuations of the said cooperating dovetail portions.

Longitudinally of the dovetail portions 10 and 11 and substantially centrally of their length and width recesses 14 and 15 are formed therein. In the recess 15, which is longer than the recess 14, a leaf spring 16 is provided. One extremity of this spring is secured as by the screw 17 to the base of the recess 15, and the opposite extremity of the said spring, which normally extends forwardly of the face of the central portion of the member 11 in which the slot 15 is formed, has a forwardly projecting lock 16a thereon. As soon as the seat portions 2 and 3 are brought into their correct relative positions the spring moves outwardly and the head or lock 16a engages the recess 14. Due to the shape of the lock and the manner in which the spring 16 is mounted there is then practically no possibility of subsequent disengagement of the lock 16a from the said recess 14.

Figure 9 shows a slightly modified arrangement wherein a second leaf spring 18 is arranged behind the free extremity of the 100

spring 16 to positively insure that the lock 16a immediately and fully engages the recess 14 and remains permanently in engagement therewith.

5 In Figure 10 another slight modification is shown. In this case tubular apertures 20 and 21 are formed in the central portions of the contiguous dovetail portions 10 and 11 respectively. These tubular apertures have 10 their axes disposed substantially at right angles to the faces of the portions 10 and 11 inwardly from which they extend. In the closed extremity of the aperture 20 a coil 15 spring 22 is provided which tends to force a lock 23 into engagement with the aperture 21.

The members 8 and 9, integral with which rearward projections 8a and 9a of lesser length are preferably provided, are held in place in their slots 6 and 7 by relatively long 20 screws 25 which extend both through the said members and their rearward projections and pierce the pieces 2, 3, 4 and 5 for such a distance that shrinkage of the material of which the said pieces are made sufficiently to leave 25 unsightly gaping joints is very unlikely to occur; particularly since no perceptible shrinkage occurs in the metallic members 8 and 9 themselves.

In order to further protect the pieces 2, 3 30 and 5 the conventional supporting arms 30, which are rotatably mounted on any preferred form of rod 30a, have apertures 31 formed through them for the passage of screws 32 which are in threaded engagement 35 with openings 33 formed in the cooperating members 8 and 9 employed in these joints. The screws 32 pass freely through clearance 40 holes formed in the pieces 2, 3 and 5 so that the weight of the seat is transmitted directly from the members to the arms 30.

Extending across the joints between the seat pieces 3, 4 and 5 plates 36 are employed, as shown in Figure 10. Through each plate 45 36 apertures 37 are formed for the passage of screws 38 which engage threaded openings 39 provided in the members 8 and 9 so the weight of the seat is transmitted from these members to conventional stops 40 carried by the plates 36 and intended to rest on the top 50 of the bowl—not shown. In the present instance the stops are made of resilient compressible material so that their lower and relatively larger portions may be forced downwardly through restricted apertures 55 36a formed substantially centrally through the plates 36.

It will therefore be seen that I have not only devised a seat having a simple and effective form of automatically engaging joint, 60 but that the seat is materially strengthened and the joints reinforced by the insertion of the metallic members to which both the supporting arms 30 and the plates 36 are directly attached.

65 While in the foregoing the preferred em-

bodiments of the invention have been described and shown, it is understood that the construction is susceptible to such alterations and modifications as fall within the scope of the appended claims.

What I claim is:

1. A toilet seat consisting of a plurality of sections in the contiguous faces of which slots are formed, members secured in said slots each opposed pair of which have cooperating dovetail portions formed on their outer faces, the outer faces of said portions having opposed recesses therein, a leaf spring mounted in one of each pair of recesses one extremity of which is secured in its recess, and an outwardly projecting head or lock on the opposite extremity of each spring which tends to engage the opposed recess formed in the outer face of the opposite and adjacent member. 70

2. A toilet seat consisting of a plurality of sections in the contiguous faces of which slots are formed intermediately of their length, metallic members in said slots, each opposed pair of members having cooperating dovetail portions formed on their outer faces, the unslotted extremities of the contiguous faces of the sections also having cooperating dovetail portions thereon which form continuations of the dovetail portions on said members, the cooperating dovetail portions of the metallic members having opposed recesses in their adjacent faces, a leaf spring mounted in one of each pair of recesses, one extremity of each leaf spring being secured to the base of its recess, and an outwardly projecting lock on the free extremity of each leaf spring which automatically engages the recess in the metallic member opposite it. 75

3. A toilet seat consisting of a plurality of sections in the contiguous faces of which slots are formed, members in said slots, cooperating faces on each adjacent pair of members, apertured supporting arms for said seat, said members having threaded openings therein, and screws extending through said arm apertures in engagement with the threaded member openings. 80

4. A toilet seat consisting of a plurality of sections in the contiguous faces of which slots are formed, members in said slots, automatic engaging means on the adjacent faces of each pair of members for holding the latter against independent movement when said members are correctly positioned relative to one another, apertured supporting arms for said seat, said members having threaded openings therein, and screws extending through said arms in engagement with said threaded openings. 85

5. A toilet seat consisting of a plurality of sections in the contiguous faces of which slots are formed, members in said slots, cooperating outer faces on each adjacent pair 90

of members, apertured plates against the underside of portions of said seat, stops projecting downwardly from said plates adapted to rest on a bowl, threaded openings in adjacent pairs of members, and screws passing through said plate apertures in engagement with said threaded openings.

6. A toilet seat consisting of a plurality of sections in the contiguous faces of which slots are formed, members in said slots, cooperating engaging surfaces on the outer faces of each pair of members, automatic engaging means on each adjacent pair of members for holding the latter against independent movement when said members are correctly positioned relative to one another, apertured plates against the underside of portions of said seat, stops projecting downwardly from said plates adapted to rest on said bowl, threaded openings in adjacent pairs of members, and screws passing through said plate apertures in engagement with said threaded openings.

7. A toilet seat consisting of a plurality of sections in the contiguous faces of which slots are formed, metallic members in said slots, each pair of members having cooperating dovetail portions formed on their outer faces, opposed recesses in said metallic members, and a spring actuated lock which extends from one recess and engages the recess opposite to it when said members are in their correct relative positions.
